ELECTROLYSIS EPILATOR

Albano Lemos, 6404 SW. 16th St., West Hollywood, Fla.

Filed Mar. 5, 1959, Ser. No. 54,849

Term of patent 14 years

(Cl. D83—12)

Fig. 1.

Fig. 2.

Fig. 3.

Fig. 4.

Fig. 5.

Fig. 6.

Fig. 1 is a front elevational view of an electrolysis epilator showing my new design;

Fig. 2 is a bottom plan view thereof;

Fig. 3 is a top plan view thereof, rotated 180°;

Fig. 4 is a rear elevational view thereof;

Fig. 5 is a left end elevational view thereof as shown in Fig. 2; and

Fig. 6 is a right end elevational view thereof as shown in Fig. 2.

I claim:

The ornamental design for an electrolysis epilator, as shown.
